MACHINE FOR MAKING BOX-PARTS

Cutler D. Knowlton, Beverly, Mass., assignor to
 Hoague-Sprague Corporation, Lynn, Mass., a
 corporation of Massachusetts

Application May 15, 1934, Serial No. 725,770

93 Claims. (Cl. 93—49)

This invention relates to machines for making box-parts or similar articles from such material as pasteboard, being especially concerned with the setting-up of blanks into box- and cover-form. 5 It is an object of the invention to simplify the construction and manner of operation of such machines and to increase the efficiency of the setting-up mechanisms and their associated elements.

10 A feature of the invention by which this object is gained consists in the direct association of box- and cover-setting-up mechanisms upon the same frame and their actuation by mechanism common to both. This common actuation also preferably extends to mechanism by which the blanks are advanced to and removed from the setting-up mechanisms. Set-up or wall-boxes, as those used 15 for marketing pairs of shoes, are always furnished with covers, and the present organization supplies a box and its cover simultaneously, so 20 that the two may be assembled immediately ready for shipment, handling of the box-parts being minimized. The number of machine elements is also reduced, as compared with independent setting-up mechanisms, as is the floor-space occupied.

25 Another feature of the invention, which is applicable as well to the manufacture of either boxes or covers separately, involves operations upon blanks at successive stations. At these stations, 30 forms are situated at different levels, and with each of these forms pressing means is preferably associated. Blanks are delivered to the first station, at which they may be partially folded and then transferred to the second station, first by 35 a vertical and then by a horizontal movement. As herein illustrated, the further folding is partially performed during transfer and partially at the second form. Since less time is required for the folding operations at the second station than 40 at the first, the duration of pressure may be increased at the former and the adhesion of the end-formations made more certain. The operation at different levels renders the transfer more simple, particularly facilitating the stripping of 45 the blank from the first form.

50 Other features of the invention have to do with the construction of the forms at the operating stations, there being a mounting allowing a form to yield to accommodate itself to pressure and to variations in thickness of the blank-material, means for expanding form-sections during the application of pressure and means for locking 55 said sections temporarily against retraction; with convenient supporting and guiding means for the forms and their directly co-operating ele-

ments; with improved means for mounting and actuating folding walls which co-operate with a form; with the actuation of the pressure members which co-operate with the forms, this being accomplished by simple rugged mechanism 5 absorbing relatively little power; with blank-supporting members which also perform an additional blank-folding function; with novel releasable means for permitting the abutment-plates co-operating with the forms to yield if clogging 10 occurs, thereby preventing breakage; and with compact mechanism for advancing blanks at different positions and for locating the blanks at one of said positions.

The accompanying drawings illustrate a particular embodiment of the invention,

Fig. 1 being a top plan view of my improved apparatus;

Fig. 2, a side elevation thereof viewed from the left in Fig. 1;

Fig. 3, an end elevation looking from the right in Fig. 2, with portions broken away and in section;

Fig. 4, a perspective view of the successively acting folding and pressing mechanisms, parts 25 being broken away;

Fig. 5, a similar view taken from the rear of Fig. 4;

Fig. 6 illustrates in broken perspective elements 30 at one of the first setting-up stations;

Fig. 7 shows, similarly, portions of one of the second setting-up stations;

Fig. 8 is a perspective view of the connecting system through which are moved the side walls at the first stations; and

Fig. 9 is a diagrammatic view in which a blank appears in successive positions during its folding and pressing.

There are preferably simultaneously produced by this apparatus a box and its cover in operating sections S and T, respectively, which are situated side by side upon a frame 10 (Fig. 1). A box-blank B which is to be formed by the apparatus appears in Fig. 9, the two lower positions showing it in its unfolded relation. It may be as disclosed in Letters Patent of the United States No. 1,811,135, dated June 23, 1931. It consists of a layer of pasteboard or other shell-material and such covering and stay-material as may be desired, having a rectangular portion or bottom a 40 from which project pairs of opposite side-wings b, b and intermediate end-wings c, c. The opposite extremities of the side-wings carry corner-laps d, d, while the end-wings are provided with extensions e, e. The meeting lines of all these 45

parts are defined by creases *f* to facilitate bending. The cover-blanks are not shown prior to the action of the apparatus upon them, but one appears as folded at C in Fig. 3 of the drawings. They have the same parts as just described for the box-blank, though the dimensions are different and the corner-laps preferably are without the denticulated ends appearing in Fig. 9. In each section of the apparatus the blanks are supported upon sets of rails 12, 12, with the end-wings at the opposite sides, and are delivered to the operating mechanisms at definite intervals by some such forwarding device as constantly traveling lugged chains 14, which deliver them between edge-gages 16, 16 at the first of two pairs of setting-up stations U and V, the latter being located upon a higher level than the former. To correctly arrange the blanks in both sections S and T for the first operation upon them, the edges of the leading side-wings are urged against stop-bars 18 (Fig. 2), carried by the frame. This is effected by fingers 20, 20, one of which is pivoted upon the entering side of each station U and is joined by a link 22 to a lever 24 pivoted upon the frame and carrying a roll 26. Each roll is situated within a cam-track formed in one face of one of two disks 28, 28 (Fig. 1) fast upon a shaft 30 journaled transversely on the main frame. Power is applied to this shaft, and to the apparatus generally, from a motor 32 through gearing 34. The fingers are so actuated by the cams that as the blanks are delivered at the stations U with their forward edges in proximity to the stop-bars 18, these fingers are lowered to leave the paths of advance unobstructed, then they rise into contact with the rear edges of the blanks and dwell momentarily to guard against rebound from the stops. Following this, they descend to their initial positions.

The setting-up operations may now be considered, it being assumed that before reaching the present apparatus each blank will have had applied to it some such adhesive as glue, which is to secure the opposite end-formations. Preferably, the coating will be upon the inner surfaces of the end-wings *c* with which the corner-laps *d* are to contact, and upon the inner surfaces of the end-wing-extensions *e* which are to be secured to the corner-laps. In each of the sections S and T, the operations and the elements by which they are performed may be substantially the same, said elements differing chiefly in size and contour. Consequently, but one of each pair of the stations U and V will generally be described. At a station U is done all the folding of the side- and end-wings and of the corner-laps of either a box or a cover, there being left unfolded only the end-wing-extensions. At this first station there is also applied pressure to effect the preliminary setting of the end-formations, which is later perfected at the succeeding station V. Each blank is received above a form 40 (Figs. 4 and 6) about which the folding is to be done. This form may consist of an integral casting cored out for the sake of lightness. It is carried upon two vertical spindles 42, 42, and to permit it to yield, for reasons which will later appear, it is mounted to move laterally upon its spindles. For this purpose there is threaded into the upper extremity of each spindle 42 a stud 44 having a reduced end 46. A hexagonal portion 48 of the stud bears upon a yoke 50 joining the spindles 42, and when rotated serves to draw together tapered surfaces at 52 upon the yoke and spindles to secure these ele-

ments to each other. Surrounding the end 46 of each stud is a sleeve 54, resting upon the hexagonal portion 48 and fixed in place by a nut 56 threaded upon the top of the stud-end. Surrounding and spaced from this sleeve is a second sleeve 58, supported upon a shoulder 60 at the bottom of a vertical bore in the form 40. The sleeve 58 is held down upon the shoulder by a cap 62 threaded into the upper end of the bore. At 64, between the sleeves 54 and 58, is interposed some such yieldable material as rubber, this preferably being vulcanized to both sleeves. It will be seen that the form 40 is free to be displaced in all directions to an extent determined by the yieldability of the material 64.

Each pair of spindles 42 carrying a form 40 are guided in the frame and secured near their lower extremities is a lower yoke 66 (Fig. 2). Articulated to a lateral extension from this yoke is a link 68 which, at its lower end, is similarly joined to a lever 70 fulcrumed upon a spindle 71 and provided with a roll 72 lying within a cam-groove in one side of a disk 74. As appears in Fig. 2, the fulcrum-portion of the lever 70 is extended laterally to give two bearings, so it may better resist lateral thrust. The disk for each of the forms of sections S and T is fixed upon one of two shafts 76, 76 journaled at opposite sides of the frame and extending longitudinally thereof. These shafts are driven by bevel-gearing 78, 78 from the transverse shaft 30. By its cam, each form is moved between a lowered position in which it receives a blank above its upper surface, as already described, into co-operation with elements by which the wings and corner-laps of the blank are to be folded and with other elements which apply pressure to the end-formations.

Referring particularly to Fig. 6, the side-wings *b* of each blank *B* are brought, by the elevation of the form, from the dotted-line position into contact with curved faces 89 upon walls 82, 82. These walls are arranged to be moved in to prevent the blank from bulging outwardly when pressure is applied to its ends. For this purpose, each wall is attached to spindles 84, 84, guided in horizontal sleeves 86 fixed to the frame (Fig. 4). One side of each spindle has rack-teeth with which meshes a gear-segment 88 extending through a slot in the sleeve and fast upon one of two transverse shafts 90, 90 (Figs. 2 and 8) rotatable upon the frame at the rear and front of the forms 40. A spring 92 is interposed between the end of each sleeve and a nut 94 threaded upon the end of its spindle. This takes up back-lash in the gearing. Above the rearward shaft 90 is journaled a shaft 96, which is joined to both of said shafts 90 by pairs of arms 98 and intermediate links 100. An arm 102 upon the shaft 96 is linked at 104 to a lever 106 provided with a roll 108 operating in a cam-groove in a disk 110 upon the shaft 30 (Fig. 1). The connections of the links 100 to the arms 98 on the shaft 96 are preferably through springs 111 to permit the actuating force to be applied yieldably to the walls 82.

As the side-wings *b* of the blank are being folded to vertical positions over the rising form by contact with the wall-surfaces 80, the corner-laps *d* are also being bent inwardly upon the side-wings by engagement with normally stationary folding members 116, which are adjustably carried upon the frame outside each of the four corners of the form. As appears in Figs. 4 and 6, each member 116 is secured to a vertical spindle 118. 75

Each spindle is mounted upon a bracket 120, provided with a screw 122 to allow the spindle to be variably clamped vertically and angularly about its longitudinal axis. The bracket is shown as secured to the frame by a slot-and-screw connection 124, so the member 116 may be adjusted in all directions horizontally. By this mounting means the time of folding of the corner-laps by surfaces 126 of the members 116 may be effected in the best relation to that of the side-wings.

Surfaces 130 upon opposite members 132 and 134 situated at the ends of the walls 82, 82, by engagement with the end-wings c of the blanks, fold these wings outside the corner-laps, bringing the parts to the full-line position of Fig. 6. These members 132 and 134 later apply pressure to the end-formations. Considering Figs. 1, 2, 3 and 4, each form 40 has at its inner extremity, or that toward the center of the frame, the stationary abutment-assembly 132, 132, while at the outer end is the movable head 134. This head is arranged to travel horizontally in ways in the frame and has at its outer side a central surface 136 inclined outward and upwardly. At each side of this surface is a rack 140, both racks being inclined similarly to the central surface. Spaced from this end of the head is an abutment 142 having a surface and racks corresponding to and horizontally aligned with those of the head, but being vertical rather than inclined. Midway between the head 134 and abutment 142 is a vertically movable actuating member 144 at each side of which the vertical surface and rack-formation are repeated. Interposed between each side of the actuating member and the abutment and head is a roll 146 contacting with the surfaces 136 and pinions 148 formed upon the roll and meshing with the racks 140. The actuating member 144 has passing through it a vertical spindle 150, which at its lower extremity has a terminal piece 152 guided in its movement by a link 154 joining it pivotally to the frame. Each terminal has rotatable upon it a roll 156 lying in a cam-groove in a disk 158 upon one of the shafts 76. The member 144 is supported upon a sleeve 160 (Fig. 2) surrounding the spindle and resting upon a spring 162 and a collar 164 threaded upon said spindle. When the forms 40 bearing the blanks with the wings and corner-laps folded arrive at the highest point in their upward travel, their ends register with the heads 134, the walls 82 having been moved in by their actuating mechanism to hold the sides of the blanks closely against the form. The cams thereupon raise the actuating members 144, which carry with them, through the gearing 140, 148, the rolls 146. Because of the inclination of the head-surfaces 136, a wedging effect is produced, and both heads 134 are forced against the end-formations of the partially set-up blanks, causing the preliminary adhesion of the end-wings to the corner-laps because of the glue which is upon the former. In this action, the cylindrical rolls transmit the pressure, the diameter of the pinions 148 being such that, without lateral compression, they are caused to travel with the members 144 and thus produce the wedging effect and consequent pressure applied by the heads 134 to the outer ends of the box. This, in turn, urges the opposite end of the form against that portion of the box and the latter against the fixed abutment 132. The slight displacement of the form is permitted by the yieldability of the mounting 64. This mounting also allows the form to yield in any direction horizontally, tend-

ing to prevent breakage if an excessive thickness of the blank-material is introduced between the pressure-applying surfaces. To return each head 134 to its normal relation upon the descent of the actuating member 144 from the active position, there are connected to opposite outward extensions 166, 166 from said head rods 167 passing through openings in the abutment 142. Springs 168 surround these rods, exerting their expansive force upon the abutment and upon nuts 169 on the threaded ends of the rods. By this simple and durable pressure mechanism, an adequate force may be exerted and frictional resistance minimized. Since the force is applied through the springs 162, it is limited by the compressibility of these springs, and this may be varied by changing the position of the collars 164 and therefore the normal degree of compression of the springs. The friction resisting the movement of the actuating members 144 is made not only small by the presence of the rolls 146 but also substantially constant. Thus, for any particular adjustment of the springs 162, the same pressure will be applied to all blanks operated upon.

Situated above and parallel to the top of each form 40 is an abutment-plate 170 secured to the lower extremity of a spindle 172. At their upper ends the spindles of the two stations U, U are attached to a common top-girt or carrier 174 (Fig. 3), which is supported upon a central vertical spindle 176 arranged to reciprocate in the frame. An arm 178 (Fig. 2) projects from one side of the spindle 176 and a link 180 joins this to a lever 182 fulcrumed upon the frame. Upon this lever turns a roll 184 acted upon by a cam-groove in the disk 158 upon the shaft 39. The movement imparted to each plate by the cam is such that it is initially separated from the form with which it registers to permit the reception of a blank, the width of this space being sufficiently narrow to hold the blank against excessive curvature, which would prevent it from properly engaging the stop 18. Then the plate is lowered into close proximity to the blank, retaining this against upward displacement upon the form during the elevation of the latter, the plate and form moving together, the plate maintaining this relation during the application of pressure at station U and leaving the blank free to center itself. Finally, it ascends when the partly finished box is transferred from station U to station V and returns to the initial position. To prevent breakage if an undue thickness of material gets between the form and the plate 170, the attachment of the latter to the end of the top-girt 174 is made yieldable. This is accomplished by securing to the upper end of the spindle 172 a cross-arm 186 guided at one end between lugs 188, 188 on the top-girt. This holds the spindle and plate against rotation. At the opposite end, the arm has a depression to receive a plunger 192 backed by a spring contained in a holder 192 pivoted upon the top-girt. Under normal operating conditions, the plunger holds the plate against movement upon the top-girt, but in event of the interposition of an abnormal thickness of material between the form and plate, the plunger yields against its spring so the plate may rise to relieve the strain upon it. By swinging the holder 192 upon its pivot the plunger may be shifted from above the cross-arm, and the spindle and plate may be lifted freely to give full access to the form and associated elements.

The above-mentioned transfer of the blanks

from stations U to stations V is accomplished for each operating section S and T by a stripper 200 normally resting in a recess in the top of each form 40. This stripper is shown in Fig. 6 5 as a skeleton plate and is mounted upon the upper end of a spindle 202 passing through an opening in the form-yoke 50. A yoke 203, guided by the spindles 42, is secured to the spindle 202 and has an extension opposite that of the yoke 10 66 and which is connected by a link 204 to a lever 206 fulcrumed upon the frame, with a roll 208 acted upon by a cam-groove in one face of a disk 210 rotated by one of the shafts 70. The control exercised by the cam over the stripper 15 causes it to rise with the form in the recess during the blank-folding and to remain in said recess while the pressure is applied. When the operations upon the blank at each station U are completed and the form descends to its initial 20 position, the stripper is elevated so the partly folded blank is separated from said form and is carried up to the level of station V. Supporting means for the blank coming into action at this upper level, the stripper descends, resuming its 25 place in the form-recess for action upon the succeeding blank.

The blank-supporting means at stations V is most clearly shown in Fig. 5. Guided one above the other to slide side by side at the rear of the 30 stations U and at the level of stations V are two carrier-rods 212, 212. Clamped to each rod for adjustment longitudinally thereof are two blocks 214, one for each station V. Attached to the blocks by slot-and-screw connections 216 are 35 supporting arms 218, a pair of arms upon different rods being at opposite sides of each station V. The forward extremity of each arm is guided by sliding engagement at 220 with rearward extensions 222 from opposite pressure-walls 224, which 40 act upon the folded blanks at stations V to apply final setting pressure. Each arm has at its inner face a horizontal supporting surface 226. While the stripper 200 at each station V holds the creases f between the end-wings c and their 45 extensions e just above the surfaces 226, the rods 212 are moved in opposite directions to force the arms 218 against the extensions so these are turned inwardly substantially at right angles to the end-wings, they now resting upon the arm-surfaces 226. This rod-movement is produced 50 by levers 228 (Fig. 2) fulcrumed at opposite sides of the frame and pivotally joined to the opposite extremities of the respective rods. Each lever has a roll 230 lying in a cam-groove in the inner 55 face of one of the disks 210. The top-plate 170 is still above the form in close proximity to the blank, preventing this from being upwardly displaced. In preparation for the forward movement of the blank into the final operating portion 60 of station V, the stripper-plate is lowered by its cam. The step of transferring the blank for folding the end-wing-extensions and applying a final setting pressure will now be described.

Again referring to Fig. 5, and also to Fig. 2, 65 journaled in blocks 231, capable of some vertical movement at the top of the frame, is a carrier-shaft 232 having the portion between its ends square in section. Upon this squared portion, clamped for adjustment longitudinally thereof to 70 correspond to the length of the blanks being operated upon, is a pair of arms 234, 234 for each station V. The lower end of each arm has secured to it a contact member 236, which has a lateral inward extension 237 normally lying just 75 at the rear of the blank when this is elevated

as just outlined. A vertical surface 239 on the member 236 holds the blank centered between the arms 218. Each arm 234 is joined by a link 238 to a slide 240 movable in ways in a guide member 242 projecting forwardly from one of the pressure-walls 224. The opposite slides of each station are shown as connected by a tie-rod 244, and upon the ends of this rod, outside the slides, are pivoted pushing fingers 245 limited in their downward movement but free to turn upwardly about their pivots. The shaft 232 is oscillated by an arm 246 fast upon the squared portion and united by a link 248 to the frame to form a toggle. This link is joined by a second link 250 to a lever 252, fulcrumed on the frame 1 and provided with a roll 254 entering a cam-groove in a disk 256 upon the shaft 30. As the shaft 232 is thus oscillated, a linkage 258 (Fig. 3) connecting to the frame the opposite end to that bearing the arm 246 maintains said shaft horizontal as it rises and falls. Arranged to turn upon the frame in front of the arms 234 is a transverse horizontal shaft 260, to which are secured downwardly curved stop-fingers 262 movable into and out of the paths of the blanks as 25 they are advanced into the forward operating portion of the stations V. The shaft 260 has an upwardly extending arm 264, articulated to which is a link 266 slotted at its opposite extremity and there guided by the pivot of the link 30 248. Projecting from one side of the link 266 is a roll 268 operating in a cam-groove formed in a forward extension 270 from the link 248. The effect of this transferring mechanism as actuated by the cam-disk 256 is as follows: The blank 35 having been freed by the descent of the form, the extensions 237 of the contact members 236 first move into engagement with the rear of the partly formed box and cover at the junctures of the bodies a and side-walls b. The members 236 40 then travel forward in practically rectilinear paths, moving the blanks over the surfaces 226 and on to aligned horizontal surfaces 272 upon the pressure-walls 224 and their rearward extensions 222. At the same time the fingers 245, guided 45 by the slides 240, are contacting with the side-walls of the box and cover completed by the previous operation of the apparatus, pushing these over the surfaces 272 and over aligned surfaces 274 upon forward extensions 276 of the walls 224. 50 Thus the box-parts are ejected from the apparatus, being carried away, if desired, by an unillustrated conveyor. As each blank is advanced by the members 236, the fingers 262, after the finished box-parts have passed beyond them, are 55 lowered by the cam-arm 270. They stop the blanks upon the surfaces 272 in the correct position for the final operation and there temporarily hold them. As the transferring elements return to their initial positions, the fingers 245 yield upwardly upon their pivots, moving over the tops of the box-parts which have just been advanced, 60 without displacing them.

A sectional form F, which at each station V folds in the glued end-wing-extensions e against 65 the surfaces of the corner-laps, is illustrated in detail in Fig. 7. The body 280 of the form is of inverted U-shape with the ends open, and movable through these openings are expandible end-sections 282, 282 resting upon a base 284 supporting the body. Vertical spindles 286, 286 70 carry the base, and these are united by connections similar to those for the form 40 at each station U, said connections terminating in a roll 288 lying in a cam-groove in the face of the disk 74 75

opposite that which actuates said form 40. Passing through an opening at the center of the base 284 is a spindle 290, having fast to its upper extremity a head 292 each end of which is pivotally joined by a link 294 to one of the form-ends 282. The spindle 290 is raised and lowered by connections generally resembling those for the stripper 200 at each station U, and including a roll 296 received by a cam-groove in the inner face of a disk 298 upon one of the shafts 76. It will be evident that as the spindle 290 is raised and lowered relatively to the form-spindles 286, the elements 292 and 294 act as toggles, expanding and contracting the form longitudinally. The spindle 290, in addition to the head 292, has secured to it below and extending outside the head a block or spacer 300, which normally lies out of contact with the end-sections 282, 282. An enlargement 302 of this spacer is situated just below opposed inner ends at the bottom of the sections, while another enlargement 304 is similarly related to the upper portions of the sections. The action of this spacer will now be described in connection with the general operation at stations V.

From its normal lowered position and with the end-sections drawn in, each form F is elevated by its spindles 286 under the influence of the cam 74 and enters between the walls of the folded blank, which is resting upon the surfaces 272. In this movement, the form engages the end-wing-extensions e, e which are now substantially horizontal and forces them up between the walls of the box-part and toward the corner-laps d. At this time, the body-portion a of the blank is just below the guides 242, which hold said blank against upward displacement. As the form approaches its highest position at which it lies fully within the walls, the spindle 290 is raised by the cam 298, more rapidly than the spindles 286, from its normal position in which the toggle-connections to the sections 282 are broken downwardly. As the toggles are thus straightened to carry the form-sections 282 against the end-wing-extensions, the pressure members 224 are simultaneously moved inwardly against the end-walls c. Although the same reference-character 224 has been applied to each of these pressure-walls included in stations V, they are preferably arranged in pairs of fixed and movable elements, as already described in connection with stations U, and may be acted upon in the same manner. The similarity of the mechanisms may clearly be seen in Fig. 4 and no further description thereof is considered necessary. The actuation of each of the movable walls at each of the stations V is effected by a cam-disk 306 upon one of the shafts 76. After the toggle members have been fully straightened, upward travel of the head 292 continues slightly past the center. At this time the enlargements 302 and 304 have been brought between the pairs of opposed walls upon the form-sections 282, and when the toggles break upwardly these walls engage both spacer-enlargements, locking the sections against further approach to each other and removing all strain from the toggles as the final pressure is applied by the walls 224. It is not necessary in this case to yieldably mount the forms F upon their spindles, since the greater length of said spindles at stations V give all the lateral yield necessary. It is to be observed that because the other operations than applying of pressure take less time at stations V than at stations U, the end-setting forces at the latter may be longer continued and secure attach-

ment by adhesion insured. At the termination of the pressure-period the walls 224 release each box-part and its form, and the toggles are broken downwardly to cause the contraction of said form, which is then lowered to its initial position, leaving the finished box-part resting upon the wall-surfaces 272. After the last action of the apparatus, the fingers 245 are advanced to eject the box and cover over the extension-surfaces 274, at the same time the preceding blank is being positioned over the forms F by the members 236 and the stop-fingers 262.

A brief outline of the operation of the apparatus will now be given, especially with reference to the successive operating steps, as illustrated in Fig. 9 of the drawings. In that figure, a box-blank B is shown at K as it approaches the setting-up mechanism of section S upon the rails 12 under the influence of the lugged feed-chains 14. A cover-blank is simultaneously being delivered to the setting-up section T. In each instance, the blanks will have received from mechanism not herein disclosed a coating of an adhesive over the appropriate areas of the end-wings and their extensions. They are brought to rest in the proper position L upon the tops of the forms 40 at stations U by the stops 18, rebound being prevented by the fingers 20 which rise behind them. Now the forms ascend, the blanks being retained against upward displacement by the abutment-plates 170 which are traveling at the same rate as the forms. Thus the side-wings b, corner-laps d and end-wings c are brought successively into engagement with the respective members 82, 116 and 132 and 134, which fold them into box-shape about the forms, save only the end-wing-extensions e. The manner in which the folding is effected may be seen in part at positions M and N. Following the folding, pressure is applied for a brief time by the members 132 and 134, as appears at O. This is sufficient to at least insure temporary adhesion of the corner-laps to the end-wings. Upon withdrawal of the members 134, the strippers 200 with the plates 170, rise and the forms 40 descend to their initial positions, the blanks being thus separated from said forms. The upward movement of the strippers with the blanks continues until the upper level at stations V is reached, as appears at P. Thereupon, the arms 218, 218 of the two pairs between which the partially folded blanks are now located approach each other, contacting with the end-wing-extensions e, so they are bent in horizontally. Following this, the strippers descend, leaving the box- and cover-blanks supported upon the arm-surfaces 226. The advancing, locating and discharging mechanisms now come into action, they operating in definite timed relation, the members 236 advancing the blanks just referred to from the arm-surfaces 226 to position Q upon the aligned surfaces 272 on the pressure members 224. At the same time, the members 245, actuated in common with the members 236, discharge from the apparatus the preceding box and cover which have been completed. As the blanks arrive upon the surfaces 272, the stop-fingers 262 are lowered by the common actuating means, so the folded blanks are correctly located above the forms F. The blanks are at this time in the final operating position at stations V. The arms 218 may now return to their normal separated relation, and the plates 170 are lowered into co-operation with the depressed forms 40. With their sec-

tions 282 retracted, the forms F rise, contacting with the horizontally bent end-wing-extensions and forcing these upwardly and outwardly as the forms enter the folded blanks. Once fully 5 within the blanks, the form-sections 282 are expanded to carry the end-wing-extensions against the corner-laps, and the members 224 move in and apply final setting pressure to the completed 10 end-formations. This step in the setting-up operations appears at R in Fig. 9. This is not a separate position, but would, in fact, coincide with the position Q, being removed horizontally therefrom to better illustrate the relation of the 15 elements. The duration of this final pressure, on account of the less time consumed in the folding and transferring operations at stations V as compared with those at stations U, may be for a greater portion of a cycle, so firm adhesion may be obtained. As the delivering members 236 and discharging members 246 return 20 to their normal positions after their active movement as just described, the fingers 262 are raised, and upon the next stroke of the members the completed box and cover are ejected, the form-sections 282 having been retracted and the forms F lowered, leaving the box and cover upon the 25 surfaces 272 for discharge over the surfaces 274. It will be appreciated that occupying a relatively small floor-space and with a reduced number 30 of actuating elements, my improved setting-up apparatus produces simultaneously both a box and its cover, delivering these together for immediate closing and packaging. The amount of handling necessary is therefore minimized and 35 the cost of production reduced.

Having described the invention, what is claimed as new and desired to be secured by Letters Patent of the United States is:

1. In a machine for setting-up box-parts, a frame, a box-form, folding members co-operating with the box-form, means for moving the box-form and its folding members relatively upon the frame to set up a box-blank, a cover-form, folding members co-operating with the 40 cover-form, means for moving the cover-form and its folding members relatively upon the frame to set up a cover-blank, an actuating member movable upon the frame, and separate connections from the actuating member to the moving means for the box-setting-up elements and the cover-setting-up elements, respectively.
2. In a machine for setting-up box-parts, a frame, a box-form, folding members co-operating with the box-form, means for moving the box-form and its folding members relatively upon the frame to set up a box-blank, box-blank-advancing means and box-removing means, each individual to the box-setting-up elements, a cover-form, folding members co-operating with the 45 cover-form, means for moving the cover-form and its folding members relatively upon the frame to set up a cover-blank, cover-blank-advancing means and cover-removing means, each individual to the cover-setting-up elements, an actuating member movable upon the frame, and separate connections from the actuating member to the moving means for the box-setting-up elements and the cover-setting-up elements, respectively, and for the box-blank-advancing and box-removing means and cover-blank-advancing and cover-removing means, respectively.
3. In a machine for setting-up box-parts, a frame, a box-form, folding members co-operat-

ing with the box-form, means for moving the box-form and its folding members relatively upon the frame to set up a box-blank, box-blank-advancing means and box-removing means, each individual to the box-setting-up elements, a cover-form, folding members co-operating with the cover-form, means for moving the cover-form and its folding members relatively upon the frame to set up a cover-blank, cover-blank-advancing means and cover-removing means, each individual to the cover-setting-up elements, a power-shaft extending transversely to the direction of travel of the blanks, boxes and covers, two shafts geared to the power-shaft and extending longitudinally of the paths of the 15 blanks, boxes and covers, such shafts being respectively individual to the box-setting-up and to the cover-setting-up elements, and operating connections between the individual shafts and their respective setting-up elements. 20

4. In a machine for making box-parts, a frame, box-setting-up mechanism mounted thereon, cover-setting-up mechanism mounted upon the frame, each mechanism being provided with a movable blank-engaging member, a carrier member 25 for said blank-engaging members, and means for moving the carrier member upon the frame.

5. In a machine for making box-parts, a frame, box-setting-up mechanism mounted thereon, cover-setting-up mechanism mounted upon the 30 frame, blank-advancing members co-operating with the respective setting-up mechanisms, a carrier member to which the advancing members are attached, and means for moving the carrier member. 35

6. In a machine for making box-parts, a frame, box-setting-up mechanism mounted thereon, cover-setting-up mechanism mounted upon the frame, each of such setting-up mechanisms being arranged at successively acting stations, and 40 mechanism carried by the frame and having elements common to both of the setting-up mechanisms and other elements individual to the respective mechanisms to effect their actuation.

7. In a machine for making box-parts, a frame, 45 box-blank-folding mechanism and cover-blank-folding mechanism mounted thereon and both arranged at successively acting stations, the elements of the folding mechanisms at the corresponding stations being movable simultaneously 50 in engagement with a box-blank and a cover-blank respectively, an actuating member, and separate connections from said member to the two folding mechanisms.

8. In a machine for making box-parts, a form 55 and folding members co-operating therewith, means movable in a substantially vertical direction for elevating partially folded blanks away from the form, and a second form upon a level higher than the first form into co-operation with 60 which the blank is elevated.

9. In a machine for making boxes and their covers, a box-form, a cover-form, folding members co-operating with each form, means for moving partially folded blanks away from the forms, 65 and a box-form and a cover-form into co-operation with which the box-blanks and cover-blanks are respectively moved.

10. In a machine for making box-parts, a form 70 and folding members co-operating therewith, means for moving partially folded blanks vertically away from the form and then horizontally, and a second form into co-operation with which the blank is thus moved.

11. In a machine for making box-parts, a form 75

and folding members co-operating therewith, means for moving partially folded blanks vertically away from the form and then horizontally, a second form into co-operation with which the blank is thus moved, and a pressure member co-operating with each form.

12. In a machine for making box-parts, means at an operating station for folding a blank and pressing the thus-folded formation, and means at a second operating station for further folding the blank and for pressing said blank for a longer time than at the first station.

13. In a machine for making box-parts from blanks having side- and end-wings, corner-laps and end-wing-extensions, means at an operating station for folding the side- and end-wings and the corner-laps of a blank, means at such station for pressing the folded ends of the blank, means at a second station for folding the end-wing-extensions of the blank, and means at such second station for pressing the completely folded ends of the blank for a longer time than pressure is applied at the first station.

14. In a machine for making box-parts from blanks having side- and end-wings, corner-laps and end-wing-extensions, means at an operating station for folding the side- and end-wings and the corner-laps of a blank, means at such station for pressing the folded ends of the blank, means at a second station for folding the end-wing-extensions of the blank, means at such second station for pressing the completely folded ends of the blank, means for transferring the partially folded blank to the second station and for effecting a partial folding of the end-wing-extensions during transfer, means at the second station for completing the folding of the end-wing-extensions, and means at such second station for pressing the completely folded ends of the blanks for a longer time than pressure is applied at the first station.

15. In a machine for making box-parts, a form, means for partially folding a blank carried by the form, means co-operating with the form to exert pressure upon the folded end-formations of the blank, a second form, means for transferring the blank from the first form to the second, means for performing upon the blank on the second form a less number of folding operations than at the first form, and means co-operating with the second form for exerting upon the folded end-formations of the completed box-part pressure for a longer time than at the first form.

16. In a machine for folding box-blanks having side- and end-wings, corner-laps and end-wing-extensions, mechanism at one station for folding the wings and corner-laps, mechanism at another station for folding the end-wing-extensions, movable means upon which the blanks are supported for advance between the stations, means for moving the supporting means into engagement with the end-wing-extensions to turn them at an angle to the wings, and mechanism at the second station for completing the folding.

17. In a machine for making box-parts, a form and blank-folding members co-operating therewith, an elevating member movable with the blank above the form, blank-supporting members to which the elevating member delivers, means for advancing the blanks over the supporting members, and a form to which the advancing means delivers.

18. In a machine for making box-parts, a form and blank-folding members co-operating therewith, a transferring member for moving the blank from the form, blank-supporting members to

which the transferring member delivers, means for advancing the blanks over the supporting members, a form to which the advancing means delivers, and pressure members co-operating with the form.

19. In a machine for making box-parts, a form and blank-folding members co-operating therewith, a transferring member for moving the blank from the form, blank-supporting means to which the transferring member delivers, means for moving the supporting members to perform a folding operation upon the blank, and a form co-operating with the supporting means.

20. In a machine for making box-parts, a form and blank-folding members co-operating therewith, an elevating member movable with the blank above the form, blank-supporting members to which the elevating member delivers, means for moving the supporting members to perform a folding operation upon the blank, means for advancing the blanks over the supporting members, a form to which the advancing means delivers, and means for moving the form into engagement with the blank-portion folded by the supporting members to complete their folding.

21. In a machine for making box-parts, a form and blank-folding members co-operating therewith, an elevating member movable with the blank above the form, an abutment member movable in co-operation with the form and with the elevating member, blank-supporting members to which the elevating member delivers, means for advancing the blanks over the supporting members, and a form to which the advancing means delivers.

22. In a machine for making box-parts, a vertically movable form, blank-folding members into co-operation with which the form is moved, a stripper movable both with and independently of the form, and folding mechanism to which the stripper delivers during a relative movement of separation between said stripper and the form.

23. In a machine for making box-parts, a vertically movable form, blank-folding members into co-operation with which the form is moved, a stripper movable both with and independently of the form, and blank-supporting members movable toward each other into engagement with a blank upon the stripper.

24. In a machine for making box-parts, a vertically movable form, blank-folding members into co-operation with which the form is moved, a stripper movable both with and independently of the form, blank-supporting members movable toward each other into engagement with a blank upon the stripper, and means for advancing the blank over the supporting members.

25. In a machine for making box-parts, a vertically movable form, blank-folding members into co-operation with which the form is moved, a stripper movable both with and independently of the form, blank-supporting members movable toward each other into engagement with a blank upon the stripper, means for advancing the blank over the supporting members, and a form movable between the supporting members into the partially folded blank.

26. In a machine for making box-parts, a vertically movable form, blank-folding members into co-operation with which the form is moved, a stripper movable both with and independently of the form, blank-supporting members movable toward each other into engagement with a blank upon the stripper, means for advancing the blank over the supporting members, and a form mov-

blank over the supporting members, a form movable between the supporting members into the partially folded blank, and a pressure member movable toward and from the form.

- 5 27. In a machine for making box-parts, a box-form and a cover-form movable side by side, a succeeding box-form and cover-form movable simultaneously with said forms, means for simultaneously delivering a box-blank and a cover-blank to their respective first-mentioned forms for folding, and means for simultaneously transferring the partially folded blanks to the second box- and cover-forms for a further folding operation.
- 15 28. In a machine for making box-parts, a box-form and a cover-form movable side by side, a succeeding box-form and cover-form movable simultaneously with said forms, means for simultaneously delivering a box-blank and a cover-blank to their respective first-mentioned forms for folding, means for simultaneously transferring the partially folded blanks to the second box- and cover-forms for a further folding operation, opposite pressure members movable toward each other to act upon blanks carried by the first associated blank- and cover-forms, and opposite pressure members movable toward each other to act upon the blanks carried by the second associated box- and cover-forms.
- 25 29. In a machine for making box-parts, a vertically reciprocatory form, folding means with which the form co-operates in its movement, horizontally movable blank-supporting members into co-operation with which a folded blank is carried, and means for moving the blank along the supporting members.
- 35 30. In a machine for making box-parts, a vertically reciprocatory form, folding means with which the form co-operates in its movement, horizontally movable blank-supporting members into co-operation with which a folded blank is carried, means arranged to vary the normal position of the supporting members toward and from each other, and means for moving the blank along the supporting members.
- 45 31. In a machine for making box-parts, a vertically reciprocatory form, folding means with which the form co-operates in its movement, horizontally movable blank-supporting members into co-operation with which a folded blank is carried, means for moving the blank along the supporting members, and a second form movable vertically into the folded blank upon the members.
- 55 32. In a machine for making box-parts, a vertically reciprocatory form, folding means with which the form co-operates in its movement, blank-supporting arms horizontally movable in engagement with a blank delivered from the form to fold said blank, and means for moving the blank as folded by the arms along said arms.
- 65 33. In a machine for making box-parts, a vertically reciprocatory form, folding means with which the form co-operates in its movement, blank-supporting arms horizontally movable in engagement with a blank delivered from the form to fold said blank, means for moving the blank as folded by the arms along said arms, and a form movable between the arms into the folded blank to complete its folding.
- 75 34. In a machine for making box-parts, movable forms situated side by side, folding means with which the forms co-operate in their movement, movable blank-supporting members co-operating with the forms, and a carrier member

to which the supporting members for plural forms are secured.

35. In a machine for making box-parts, two movable forms situated side by side, folding means with which the forms co-operate in their movement, movable blank-supporting members situated at opposite sides of each form, and two movable carrier members to which the supporting members at the same side of the forms are respectively secured.

10 36. In a machine for making box-parts, movable forms situated side by side, folding means with which the forms co-operate in their movement, movable blank-supporting members co-operating with the forms, two rods movable oppositely transversely of the direction of movement of the forms, and two blank-supporting arms secured to each rod and co-operating with the forms.

15 37. In a machine for making box-parts, movable forms situated side by side, folding means with which the forms co-operate in their movement, movable blank-supporting members co-operating with the forms, two rods movable oppositely transversely of the direction of movement of the forms, two blank-supporting arms secured to each rod and co-operating with the forms, and means arranged to fix the arms at different points along the rods.

20 38. In a machine for making box-parts, a form, pressure members co-operating with opposite sides of the form, and supporting members upon which blanks are advanced to the form, said supporting members being guided by engagement with the pressure members.

25 39. In a machine for making box-parts, a form, pressure members co-operating with opposite sides of the form, and supporting members upon which blanks are advanced to the form, said pressure members and supporting members having aligned blank-supporting surfaces and having engagement to effect the alignment while permitting relative movement.

35 40. In a machine for making box-parts, a stationary abutment, an opposite movable head, a form upon which box-parts are pressed between the head and abutment, a reciprocatory carrier for the form, and connections between the form and carrier permitting yield of the form laterally upon the carrier in all directions.

45 41. In a machine for making box-parts, a stationary abutment, an opposite movable head, a form upon which box-parts are pressed between the head and abutment, a reciprocatory carrier for the form, and yieldable material surrounding the carrier within the form.

55 42. In a machine for making box-parts, pressure means, a form upon which box-parts are pressed, a form-supporting spindle, inner and outer sleeves and a layer of yieldable material interposed between the sleeves, and means for securing the sleeves respectively to the spindle and form.

65 43. In a machine for making box-parts, opposite pressure members, a form situated between the members and having sections movable toward and from said members in the application of pressure to a box-part on the form, and a unitary actuating member movable in co-operation with the form to separate and retract the sections, the actuating member being movable between and receiving contact of the sections to lock them against retraction.

70 44. In a machine for making box-parts, opposite pressure members, a form situated be-

5   between the members and having sections movable toward and from said members in the application of pressure to a box-part on the form, an actuating member movable in co-operation with the form, and links connecting the actuating member and the sections, said actuating member being movable into locking relation between the sections as these are separated by the action of the links and relieving said links of pressure.

10   45. In a machine for making box-parts, opposite pressure members, a form situated between the members and having sections movable toward and from said members in the application of pressure to a box-part on the form, an actuating member movable in co-operation with the form, and links connecting the actuating member and the sections and furnishing therewith toggles which may be straightened by movement of the actuating member to separate the sections, said actuating member receiving contact of the sections when the toggles pass the straightened position.

15   46. In a machine for making box-parts, opposite pressure members, a form situated between the members and having a U-shaped body-portion and sections movable through open ends of the body, a head movable vertically within the body between the sections, and connections between the head and sections to separate and retract said sections.

20   47. In a machine for making box-parts, opposite pressure members, a form situated between the members and having a U-shaped body-portion and sections movable through open ends of the body, a head movable vertically within the body between the sections, and connections between the head and sections to separate and retract said sections, the head having locking portions movable between the sections.

25   48. In a machine for making box-parts having folded end-formations, a form over which the box is folded, pressure members acting upon the end-formations, movable walls arranged for retaining engagement with the opposite sidewalls of the box, an actuating shaft situated at one side of the form, and connections from the actuating shaft to both retaining walls.

30   49. In a machine for making box-parts, a form, movable walls situated at opposite sides of the form and contacting with a box-blank thereon, a shaft journaled adjacent to each wall, gearing connecting each shaft to the adjacent wall, an actuating shaft common to the geared shafts, linkages joining the actuating shaft to the geared shafts, and means for oscillating the actuating shaft.

35   50. In a machine for making box-parts, a form, movable walls situated at opposite sides of the form and contacting with a box-blank thereon, a shaft journaled adjacent to each wall, gearing connecting each shaft to the adjacent wall, an actuating shaft common to the geared shafts, linkages joining the actuating shaft to the geared shafts, each linkage including a yieldable element, and means for oscillating the actuating shaft.

40   51. In a machine for making box-parts, a frame, a form movable therein, a wall co-operating with the form, spindles extending from the wall and being spaced one from another thereon and movable in a stationary portion of the frame, and means for reciprocating the spindles through said frame.

45   52. In a machine for making box-parts, a frame, a form movable therein, a wall co-operating with the form, spindles extending from the wall and being movable in the frame, means for reciprocating the spindles, and springs surrounding the spindles for normally drawing the walls from the form.

50   53. In a machine for making box-parts, a frame, a form movable therein, a wall co-operating with the form, spindles extending from the wall and being movable in the frame, a shaft extending transversely of the spindles, and gearing connecting the shaft and spindles.

55   54. In a machine for making box-parts, a frame, a plurality of forms movable therein, a movable wall co-operating with each form, a shaft extending along the forms, and connections from the shaft to all the walls for moving them.

60   55. In a machine for making box-parts, a frame, a plurality of forms movable therein, movable walls co-operating with the opposite sides of each form, shafts extending along the opposite sides of the forms, connections from each shaft to all the walls at the same side of the forms, and actuating means common to the two shafts.

65   56. In a machine for making box-parts, a form, a pressure member movable toward and from the form, an actuating member movable transversely of the path of the pressure member, the actuating member and pressure member having opposite surfaces lying at an angle to each other in the direction of movement of the actuating member, and a member contacting with the opposite surfaces to transmit the movement of the actuating member to the pressure member.

70   57. In a machine for making box-parts, a form, a pressure member movable toward and from the form, an actuating member movable transversely of the path of the pressure member, the actuating member and pressure member having opposite surfaces lying at an angle to each other in the direction of movement of the actuating member, a member contacting with the opposite surfaces to transmit the movement of the actuating member to the pressure member, and connections for applying power yieldably to the actuating member.

75   58. In a machine for making box-parts, a form, a pressure member movable toward and from the form, an actuating member movable transversely of the path of the pressure member, the actuating member and pressure member having opposite surfaces lying at an angle to each other in the direction of movement of the actuating member, and a member contacting with the opposite surfaces to transmit the movement of the actuating member to the pressure member, the transmitting member being movable by the actuating member.

80   59. In a machine for making box-parts, a form, a pressure member movable toward and from the form, an actuating member movable transversely of the path of the pressure member, the actuating member and pressure member having opposite surfaces lying at an angle to each other in the direction of movement of the actuating member, and a member having a portion contacting with the opposite surfaces to transmit the movement of the actuating member to the pressure member and another portion causing movement of the transmitting member by the actuating member.

85   60. In a machine for making box-parts, a form,

- a pressure member movable toward and from the form, an actuating member movable transversely of the path of the pressure member, the actuating member and pressure member having opposite surfaces lying at an angle to each other in the direction of movement of the actuating member, and a movement-transmitting roll contacting with the opposite surfaces.
61. In a machine for making box-parts, a form, a pressure member movable toward and from the form, an actuating member movable transversely of the path of the pressure member, the actuating member and pressure member having opposite surfaces lying at an angle to each other in the direction of movement of the actuating member, and a movement-transmitting roll contacting with the opposite surfaces, the roll being geared to the pressure member and to the actuating member.
62. In a machine for making box-parts, a form, a pressure member movable toward and from the form, an abutment spaced from the pressure member, a reciprocating actuating member movable transversely to the path of the pressure member between it and the abutment, there being upon the pressure member, abutment and actuating member co-operating surfaces one of which is inclined in the direction of reciprocation of the actuating member, and means interposed between the surfaces to cause a wedging action during such reciprocation.
63. In a machine for making box-parts, a form, a pressure member movable toward and from the form, an abutment spaced from the pressure member, there being extensions from the pressure member having portions passing through the abutment, and springs situated between the pressure member extensions and the outer side of the abutment.
64. In a machine for making box-parts, a form, a pressure member movable toward and from the form, an abutment spaced from the pressure member, an actuating member movable transversely of the path of the pressure member between it and the abutment, a roll contacting with one side of the actuating member and with the pressure member, and a roll contacting with the opposite side of the actuating member and with the abutment.
65. In a machine for making box-parts, a form, a pressure member movable toward and from the form, an abutment spaced from the pressure member, an actuating member movable transversely of the path of the pressure member between it and the abutment, a roll contacting with one side of the actuating member and with the pressure member, a roll contacting with the opposite side of the actuating member and with the abutment, and gearing connecting each roll with both elements with which it contacts.
66. In a machine for making box-parts, a form, a pressure member movable toward and from the form and having at the side removed from the form a surface inclined upwardly and outwardly, a vertically reciprocating member spaced from the pressure member and having a vertical surface, and a roll contacting with both surfaces.
67. In a machine for making box-parts, a form, a pressure member movable toward and from the form and having at the side removed from the form a surface inclined upwardly and outwardly, a vertically reciprocating member spaced from the pressure member and having a vertical surface, racks at opposite sides of the surfaces of both members, and a roll contacting with both surfaces and carrying at its ends pinions meshing with the racks.
68. In a machine for making box-parts, a form, a pressure member movable toward and from the form and having at the side removed from the form a surface inclined upwardly and outwardly, a vertically reciprocating member spaced from the pressure member and having vertical surfaces at its opposite sides, an abutment at the opposed side of the reciprocating member from the pressure member, said abutment being provided with a vertical surface, and rolls contacting with the opposed surfaces of the reciprocating member and the pressure member and abutment.
69. In a machine for making box-parts, a form, a pressure member movable toward and from the form and having at the side removed from the form a surface inclined upwardly and outwardly, a vertically reciprocating member spaced from the pressure member and having vertical surfaces at its opposite sides, an abutment at the opposite side of the reciprocating member from the pressure member, said abutment being provided with a vertical surface, rolls contacting with the opposed surfaces of the reciprocating member and the pressure member and abutment, and gearing connecting the rolls and the reciprocating member, the pressure member and the abutment.
70. In a machine for making box-parts, a stationary abutment, a form co-operating with the abutment, a mounting for the form permitting it to yield toward and from the abutment, and a pressure member acting upon the form at the side opposite the abutment.
71. In a machine for making box-parts, a stationary abutment, forms co-operating with opposite sides of the abutment, and a pressure member acting upon each form at the side opposite the abutment.
72. In a machine for making box-parts, a stationary abutment, forms co-operating with opposite sides of the abutment, a yieldable mounting for each form, and a pressure member acting upon each form at the side opposite the abutment.
73. The combination with a frame, of spaced spindles guided therein, a form carried by the spindles, a yoke connecting the spindles, means for applying power to the yoke to reciprocate the form, a spindle co-operating with the form, and a yoke secured to the last-mentioned spindle and guided by the form-spindles.
74. The combination with a frame, of spaced spindles guided therein, a form carried by the spindles, a yoke connecting the spindles, a spindle co-operating with the form, a yoke secured to the last-mentioned spindle and guided by the form-spindles, the yokes having opposite extensions, and connections to the yoke extensions for reciprocating the spindles.
75. The combination with a frame, of spaced spindles guided therein, a form carried by the spindles, a yoke connecting the spindles, means for applying power to the yoke to reciprocate the form, a spindle extending through the form and carrying a stripper, and a yoke secured to the last-mentioned spindle and guided by the form-spindles.
76. The combination with a frame, of spaced spindles guided therein, a form carried by the spindles and provided with extensible sections, a yoke connecting the spindles, means for applying power to the yoke to reciprocate the form, a spindle connected to the form-sections, and a yoke secured to the last-mentioned spindle and guided by the form-spindles.

77. In a machine for making box-parts, a form, a reciprocating spindle, a carrier secured to the spindle, a spindle movable longitudinally in the carrier, a plate attached to the last-mentioned spindle and co-operating with the form, and a spring interposed between the plate-spindle and the carrier.

78. In a machine for making box-parts, a form, a reciprocating spindle, a carrier secured to the spindle, a spindle movable longitudinally in the carrier, a plate attached to the last-mentioned spindle and co-operating with the form, a holder movable upon the carrier, and a spring mounted upon the holder and acting upon the form-spindle.

79. In a machine for making box-parts, a form, a reciprocating spindle, a carrier secured to the spindle, a spindle movable in the carrier, a plate attached to the last-mentioned spindle and co-operating with the form, a holder pivoted upon the carrier, and a spring-plunger contained in a holder and movable thereby to yieldably retain the plate in co-operation with the form or to free the plate for separation from the form.

80. In a machine for making box-parts, a form, a reciprocating spindle, a carrier secured to the spindle, a spindle movable in the carrier, a plate attached to the last-mentioned spindle and co-operating with the form, an arm secured to the form-spindle, a guide at one end of the arm engaging the carrier, and a spring co-operating with the opposite extremity of the arm.

81. In a machine for making box-parts, a form, a reciprocating spindle, a carrier secured to the spindle, a spindle movable in the carrier, a plate attached to the last-mentioned spindle and co-operating with the form, an arm secured to the form-spindle, a guide at one end of the arm engaging the carrier, a spring, and a holder for the spring by which it may be moved into and out of active cooperation with the arm.

82. In a machine for making box-parts, a box-form, a cover-form, a spindle movable between the forms, a carrier extending from the spindle above the forms, spindles movable in opposite extremities of the carrier, a plate attached to each of the last-mentioned spindles and co-operating with one of the forms, and a spring interposed between each spindle and the carrier.

83. In a machine for operating upon box-parts, means for operating upon blanks at different positions, a member movable to advance blanks from one position to another, a member movable into and out of the path of the blanks to locate them at the receiving position, and connections to the advancing member and to the locating member for moving them in timed relation.

84. In a machine for operating upon box-parts, means for operating upon blanks at one position, a member movable to advance blanks from such position to another operating position, a member movable into and out of the path of the blanks to locate them at the receiving position, means for operating upon the blanks as thus located, and a member for removing the blanks from said receiving position.

85. In a machine for operating upon box-parts,

means for operating upon blanks at different positions, a member movable to advance blanks from one position to another, a member movable into and out of the path of the blanks to locate them at the receiving position, a member for removing the blanks from said receiving position, and connections to the advancing member, the locating member and the removing member for operating all in timed relation.

5

86. In a machine for operating upon box-parts, means for operating upon blanks at different positions, an oscillatory shaft, blank-advancing members movable at one position, a second blank-advancing member movable at another position, a stop member movable into and out of the path of the blanks, and actuating connections from the shaft to all of said members.

87. In a machine for operating upon box-parts, means for operating upon blanks at different positions, an oscillatory arm having advancing engagement with the blanks at one position, a slide connected to the arm, and a member carried by the slide for contact with a blank at another position.

20

88. In a machine for operating upon box-parts, means for operating upon blanks at different positions, an oscillatory blank-advancing arm operating at one position, a cam movable with the arm, and a blank-stop actuated by the cam.

89. The combination with mechanism for operating upon blanks, of a toggle supported at one extremity, a shaft oscillated and moved bodily by the opposite extremity of the toggle, a blank-advancing arm carried by the shaft, and means for oscillating the supporting arm of the toggle.

30

90. The combination with mechanism for operating upon blanks, of a toggle supported at one extremity, a shaft oscillated and moved bodily by the opposite extremity of the toggle, a blank-advancing arm carried by the shaft, means for oscillating the supporting arm of the toggle, a slide, a blank-advancing member carried by the slide, and a link joining the slide to the toggle.

40

91. The combination with mechanism for operating upon blanks, of a pivoted arm, means for oscillating the arm, a stop-lever for the blanks at the operating mechanism, a link joined to the stop-lever and guided by the arm-pivot, and a cam carried by the arm and acting upon the link.

50

92. The combination with mechanism for operating upon blanks, of a pivoted arm, means for oscillating the arm, a shaft oscillated by connection to the arm, a blank-advancing member carried by the shaft, a stop-lever for the blanks at the operating mechanism, a link joined to the stop-lever, and a cam carried by the arm and acting upon the link.

55

93. The combination with mechanism for operating upon blanks, of a pivoted arm, means for oscillating the arm, a shaft oscillated by connection to the arm, a blank-advancing member carried by the shaft, a second blank-advancing member connected to the first, a stop-lever for the blanks at the operating mechanism, a link joined to the stop-lever, and a cam carried by the arm and acting upon the link.
